UNITED STATES PATENT OFFICE.

RALPH S. ROBERTS AND CLARENCE E. WEXELBERG, OF DETROIT, MICHIGAN, AS-SIGNORS TO BRIGGS MANUFACTURING COMPANY, OF DETROIT, MICHIGAN, A CORPORATION OF MICHIGAN.

FRONT-END CONSTRUCTION.

Application filed November 28, 1927. Serial No. 236,334.

This invention relates generally to the body construction of vehicles of the closed car type and refers more particularly to the front end construction of such vehicles.

5 One of the primary objects of the present invention is the provision of a novel means of assembling the visor to the front body portion of the vehicle whereby a neat and pleasing appearance of the front of the

10 body is effected.

With these and other objects in view, the invention resides in certain novel features of construction, combinations and arrangements of parts as will be more fully described and particularly pointed out in the appended claims.

In the drawings:

Figure 1 is a perspective view of the front end construction with the visor and deck 20 covering removed.

Figure 2 is another perspective view of the front end construction with the parts assembled.

Figure 3 is a vertical sectional view.

25 Referring particularly to Figure 1 the numeral 10 indicates the forward portion of a closed vehicle body comprising the front corner posts 11 and 12 extending upwardly from the cowl 13. As shown, a windshield header 14 is suitably supported between these posts while a pair of roof rails 15 extend rearwardly from the posts and form part of the roof structure which may be of the regular construction.

35 The numeral 16 represents a front cross member adapted to be secured upon the top of the header in advance of the roof construction and having its end portions resting on the header 14 and secured to the forward ends of the roof rails 15. Preferably the front face of this cross member 16 is of bowed formation, the arrangement being such that the central intermediate portion overhangs the front wall of the header as at 17 while the end portions of the cross member are disposed in the rear thereof and form with the header rabbets 18, the purpose of which will be presently described. In completing the construction shown in Figure 1 a deck covering 19 is first applied to the roof in any preferred manner, the front edge of this covering terminating upon the top of the cross member 16. A visor 20 is next applied to the front

of the body and is provided with a bowed 55 vertical portion 21 corresponding in design to the front face of the cross member 16. It will now be apparent that by providing the rabbets 18 at each end of the header, ample supporting surfaces are provided for 60 retaining the end portions of the visor in position.

Preferably the cross member 16 is grooved to provide a rabbet 21' for receiving a rearwardly projecting flange portion 22 of the 65 visor wall 21, while a finish molding 23 is provided for securing and concealing the edges of the visor and deck covering and at the same time providing a neat corner finish. As shown, this molding has a depending 70 flange 24 seating upon the flange portion 22 and retaining the same in engagement with the rabbet 21' of the cross member.

From the foregoing it will be apparent that we have provided a novel means of 75 assembling a visor to the front portion of a vehicle body and at the same time have provided a design which is pleasing in appearance and which greatly adds to the general appearance of the vehicle. 80

What we claim as our invention is:

1. In a vehicle body construction, a windshield header, and a front cross member supported upon said header having an intermediate portion overhanging said header and 85 having its end portions disposed in the rear of the front wall of said header and forming rabbets with said header.

2. In a vehicle body construction, a windshield header, and a front cross member of 90 bowed formation supported upon said header having its central portion overhanging said header and having its end portions disposed in the rear of the front wall of said header and forming rabbets with said header. 95

3. In a vehicle body construction, a windshield header, a front cross member of bowed formation supported upon said header having its central portion overhanging said header and having its end portions disposed in the rear of the front wall of said header and forming rabbets with said header, and a visor for said vehicle having a bowed portion 100 engaging the bowed portion of said cross member, said visor having other portions engageable with and supported upon said rabbets. 105

4. In a vehicle body construction, a windshield header, a front cross member supported upon said header and provided with a rabbet in its front wall, a visor for said vehicle having a flange engageable with the front wall of said cross member, said visor flange having a rearwardly projecting portion engaging the rabbet aforesaid, and a finish molding secured to the top of said cross member and having a depending flange engageable with the rearwardly projecting portion of said visor for retaining the same in the rabbet.

5. In a vehicle body construction, the combination with a windshield header, of a front cross member supported upon said header, and having an intermediate portion overhanging the front wall of said header and having end portions in rear of the front wall of said header, and a visor having attaching portions on the overhanging portion of said cross member and on certain portions of said header.

6. In a vehicle body construction, the combination with a windshield header, of a front cross member supported upon said header having an intermediate portion overhanging

the front wall of said header and having end portions in rear of the front wall of said header and forming rabbets therewith, said overhanging portion being provided at its forward edge with a longitudinally extending rabbet, and a visor having attaching portions secured in the rabbets aforesaid including the rabbet in said overhanging portion.

7. In a vehicle body construction, the combination with a windshield header, of a front cross member supported upon said header having an intermediate portion overhanging the front wall of said header and having end portions in rear of the front wall of said header, a visor having attaching portions on the overhanging portion of said cross member and on certain portions of said header, a top covering extending over said cross member, and a finish strip having portions on said top covering and visor and concealing the joints between said visor and said cross member.

In testimony whereof we affix our signatures.

CLARENCE E. WEXELBERG.
RALPH S. ROBERTS.
